UNITED STATES PATENT OFFICE.

OLAF M. HUSTVEDT AND HARRY J. NICHOLS, OF WASHINGTON, DISTRICT OF COLUMBIA.

SPOTTING PROJECTILE.

Application filed August 30, 1920, Serial No. 408,407. Renewed August 29, 1922. Serial No. 585,079.

To all whom it may concern:

Be it known that we, OLAF M. HUSTVEDT and HARRY J. NICHOLS, citizens of the United States, and residents of Washington, District of Columbia, have invented certain new and useful Improvements in Spotting Projectiles, of which the following is a specification.

This invention relates to improvements in projectiles and more particularly to that type which, from their use may be called spotting projectiles. The projectiles, after being fired and upon striking the surface of a body of water or any obstructions are so constructed and arranged as to discharge a body of chemicals which produce a colored signal according to the materials or ingredients used.

This type of projectile is of particular value in military operations in identifying the spot where a particular projectile strikes when guns are fired in salvo, thereby enabling fire control to be regulated very exactly. It is of particular value in calibrating the several guns of a ship or battery. Heretofore no means of identifying the fall of shot from each individual gun when fired in salvo has been available, hence it has often occurred that when so fired the shot from some guns has been found to fall widely apart from the other guns, thereby resulting in a large dispersion or pattern, rendering the battery less effective against hostile forces. The invention herein described provides a means of identifying the fall of shot from each gun, thereby permitting the undesirable condition described above to be remedied by suitable measures of adjustment.

It is also of value in gunnery exercises in disclosing the fall of shot from each individual gun or turret, whether the shot strikes the target or not. It is to be understood that heretofore in salvo firing, in target practice, only those shots which struck the target could be identified with certainty, this identification being secured by painting the projectile with different colors, the color being rubbed off on the target as the shot passed through. The invention herein described will enable the "misses" to be identified with as much certainty as the "hits" are now identified.

A projectile of this type is also of value in identifying the salvos of different ves-

sels or batteries which may be firing at the same target, their fire being controlled independently. If shots or salvos from such vessels or batteries be so fired as to strike simultaneously, or nearly so, it is difficult to identify the particular shot in salvo with the vessel or battery from which it was fired. By use of the spotting projectile hereinafter described this identification may be made with certainty and the necessary corrections to the fire be properly applied. In this case each ship or battery would be supplied with projectiles giving signals of one color.

It is therefore one of the objects of the present invention to overcome the objections above cited, and to provide a simple and practical construction which will enable the objects of the spotting shell to be realized in a reliable manner.

Broadly speaking, the invention provides means of ejecting various coloring materials, such as pigments, dyes and other chemicals from a projectile in such a way as to color the splash of the projectile, or to form a colored cloud of particles of the chemicals which float briefly in the air, thereby producing a distinctive signal visible for long distances.

Other objects will be in part obvious or apparent to those skilled in the art of gunnery or in part hereinafter more fully pointed out.

Referring now to the drawings in detail showing two of various possible embodiments of the invention and wherein like parts are denoted by corresponding reference characters.

Figure 1 illustrates one embodiment of the invention in which the projectile is fitted with an igniter adapted to be secured in the nose of the projectile.

Figure 2 is a sectional view of a projectile fitted to receive an igniter of the type generally known as a base fuse.

Figure 3 is a diagrammatic view showing the method of use.

Referring to the drawings in detail and in particular to Figure 1, the numeral 1 indicates the shell body of the projectile which is fitted with a detachable base plug 2 secured in the shell body in any suitable manner, as for example, in Figure 1 by anti-shear pins 12 and anti-twist pins 13 and in Figure 2 by the screw joint 3 which

2

rovides less threads than are generally employed. The shell body is also fitted with rotating band 4 and a threaded opening 5 into which the igniter 6 is screwed. This igniter may be of any desired type and is merely shown conventionally in the drawings. The interior of the projectile is divided into two compartments by a partition 9 which is preferably composed of hard wax or cement. The space in front of the partition 9 is occupied by an explosive 7 which may be of any desired composition. The space to the rearward of the partition is occupied by coloring material 8 which may be of various compositions to secure distinctive coloration. While it is to be understood that the invention is not to be restricted as to the coloring material employed, it is suggested that pigments commonly employed in paint making, such as ultramarine, chrome yellow, chrome green, vermilion, etc., may be used for they have been found to produce the desired effect, as are also dyestuffs of various natures, both soluble and insoluble in water, as well as yestuffs mixed with diluent materials.

In Figure 2 is shown an embodiment of his projectile in which an igniter or detonator of the type known as a base fuse is used. In this embodiment the ejection charge 7 is separated from the coloring material 8 by a metallic diaphragm 10, which has a threaded seat in the shell cavity and as a threaded orifice to receive any desired type of igniter or detonator, 11.

In Figure 3 there is shown a method whereby the determination of the errors of gun fire is made possible in which it may be assumed that a broadside of four heavy calibre guns are fired in salvo at a target. It may be further assumed that three of these guns shoot accurately and will give respectively green, yellow, and blue splashes. The fourth gun, however, may be assumed to be shooting inaccurately and the splash of the projectile to be colored red. It is, of course, to be understood that before firing each gun is loaded with a projectile having a known coloring compound and in this manner the inaccurate gun can at once be detected, and the nature and amount of its error determined. A similar process, of course, may be followed out whereby the determination of the errors of collective gun fire of a plurality of ships or batteries is made possible. In the carrying out of such a process it is preferable to use the same coloring pigments in all the shells fired from one ship or battery as distinguished from those of another.

It is thus seen that the present invention provides a simple and practical projectile or an attachment for a projectile adapted to accomplish among others the objects herein set forth. From the various colors

used in different projectiles it is possible to note exactly where each projectile lands from each gun when the guns are fired in salvo thus permitting a calibration of the guns with less cost, in much less time and with greater accuracy than has heretofore been possible.

Without further analysis, the foregoing will so fully reveal the gist of this invention that others can, by applying current knowledge, readily adapt it for various applications without omitting certain features that, from the standpoint of the prior art, fairly constitute essential characteristics of the generic or specific aspects of this invention, and, therefore, such adaptations should and are intended to be comprehended within the meaning and range of equivalency of the following claims.

What we claim is:—

1. A projectile provided with a chamber, a colored pigment within said chamber and means within the projectile to eject and disperse the colored pigment at the moment of impact of the projectile.

2. In a projectile, in combination, a removable base block providing a chamber containing a color compound, an explosive charge relatively forward of said chamber, and means for igniting or detonating the explosive charge and ejecting the color compound from the base of the projectile on impact.

3. A projectile having an elongated chamber, a removable block closing said chamber at the base of the projectile, an ejecting charge, and a color compound interposed between the ejecting charge and the base block and means for igniting or detonating the ejecting charge on impact whereby the color compound is ejected at the moment of impact to indicate where the projectile fell.

4. A projectile provided with a chamber, a colored pigment within said chamber and means to eject and disperse the colored pigment at the moment of impact of the projectile, said means including an ejecting charge located forwardly of the pigment whereby the pigment is ejected through the rear of the projectile.

5. A projectile provided with a chamber, a colored pigment within said chamber, means to eject and disperse the colored pigment at the moment of impact of the projectile, said means including an ejecting charge located forwardly of the pigment whereby the pigment is ejected through the rear of the projectile and impact fuse mechanisms adapted to ignite or detonate said ejecting charge.

6. The herein described method whereby determination of the errors of salvo gun fire is made possible which consists in loading each gun with a projectile having the known diffusible pigment adapted to color

the splash or make a colored cloud on impact, firing said guns in salvo and identifying the fall of the projectile from each gun by the different colored splashes or clouds 5 produced by the differently colored diffusible pigments.

7. The herein described method whereby determination of the errors of collective gun fire is made possible which consists in loading the guns of each battery with projectiles 10 having the same known diffusible pigment adapted to color the splashes or make a colored cloud on impact, firing the guns in salvo from all batteries and observing and noting the fall of the salvo from each battery 15 by the different colored splashes or clouds produced by the differently colored diffusible pigments.

8. The herein described method of identifying the fall of projectiles of individual 20 guns fired in salvo which consists in the

steps of firing from each gun a projectile having a known diffusible pigment adapted to make a colored cloud or splash on impact and identifying the fall of the projectile 25 from each gun by the different colored clouds or pigments produced by the differently colored splashes.

9. In a projectile provided with a chamber, a coloring matter within said chamber, 30 and means to eject said matter at the moment of impact of the projectile.

10. In a projectile provided with a chamber, a coloring matter within said chamber, 35 and means to eject said matter rearwardly from said chamber upon impact of the projectile with its objective.

Signed at Washington, District of Columbia, this 12th day of July, 1920.

OLAF M. HUSTVEDT.
HARRY J. NICHOLS.
